UNITED STATES PATENT OFFICE.

JAMES M. BURNAP, OF CHICAGO, ILLINOIS.

FOOT-WASHING SLIPPER.

Application filed November 15, 1926. Serial No. 148,551.

This invention relates to improvements in foot washing slippers.

The main object of the invention is to provide a device in the nature of a fabric slipper, which is adapted to be removably secured to the inclined end of either a foot tub or a regular bath tub, the slipper being adapted to receive and engage the foot with a yielding pressure, so that when the foot is moved back and forth therein, every part of the foot will be subjected to a scouring action, and thereby thoroughly cleansed.

Further, to provide a slipper comprising a suitable fabric body or jacket and a series of spaced resilient foot surrounding ribs which are removably secured to the jacket, and which are of varying shapes in cross section, to give a slipper-like form to the jacket, the said jacket being open at the toe end and along the top thereof to permit the insertion of the foot in the washing process, the slipper being somewhat longer than the foot to permit a back and forth scouring movement of the foot therein.

These objects are accomplished by the device illustrated in the accompanying drawings, in which:

Figure 1 is a side view of one form of the improved foot washing slipper, showing the manner of its connection to the inclined end of a foot tub.

Fig. 2 is an enlarged side view of the slipper shown in Figure 1;

Fig. 3 is a plan view of a slipper having an open heel end;

Fig. 4 is a transverse sectional view through the slipper; and

Fig. 5 is a side view of a portion of a slipper showing a heel portion in hinged engagement with the body portion of the slipper.

Referring to the accompanying drawings:

The numeral 1 indicates a foot tub having one end 2 thereof inclined at an angle of approximately forty-five degrees, and to this inclined end is removably secured the improved foot washing slipper A. While I have shown a foot tub, the invention also contemplates the use of a full sized bath tub, in which case two of the improved slippers may be used to permit the washing of both feet at one time. The improved slipper, in its preferred form comprises a foot encasing member which is made of suitable heavy fabric material, which is of a size and

shape to be folded around and partly over the top of the foot, leaving a relatively wide opening at the toe end and a much narrowed opening along the top which extends back to the heel, where the opposite sides of the fabric are shaped to fold around the heel. The fabric or jacket, as it will hereafter be termed, is made to conform somewhat to the shape of the foot, and is retained in such shape by a series of spaced resilient ribs 3, which extend under and around the jacket and to within a slight distance of the edges thereof which define the opening in the slipper. The ribs 3 are of varying sizes and shapes to conform to varying thicknesses of the foot from the toes back to the ankle. These ribs are of steel or other resilient metal and are bent to form base portions, which support the sole of the jacket and which are arched, as shown in Figure 4, and side members which are bent to conform somewhat to the cross sectional outline of the foot. The ribs are placed around the jacket at suitable intervals from the toe end to within a short distance of the heel, and are secured to the jacket, preferably by split pins 10, which are passed through the pad and through holes in the said ribs, the ends of the pins being spread in the usual manner to hold them in place. This arrangement permits quick and easy removal of the ribs, to permit washing of the jacket, or the attachment of the ribs to a new jacket. In practice, the heel may be closed, as shown in Figures 1 and 2, or open, as shown in Figure 3. When a closed heel jacket is used, it is properly cut to fold around the heel and the folded heel portion is inclosed or surrounded by a thin metal form 4, which is pressed or stamped to conform to the contour of the heel, and the form is secured to the heel portion of the pad by split pins, as in the case of the ribs.

The slipper is enough longer than the foot to permit a back and forth scouring movement of the foot therein, and is of a height to extend to the ankle joint. To the arch portion of the rearmost ribs is secured one end of a hook rod 5, which extends back beneath the heel of the jacket, its free end being bent to form an eye, and a similar hook rod 7 is secured to the arched portion of the rib nearest the toe of the jacket.

The inclined end of the tub is provided near its lower portion with a hook 6, over

which is passed the eyed end of the hook rod 5, and one end of a coil spring 8 is secured to the hook rod 7, and the other end of the spring terminates in a hook 9, which 5 engages the rolled upper edge of the inclined end of the tub, the coil spring being under tension when thus hooked, so as to hold the slipper in proper footwashing position.

When the open heel pad is used, the ribs 10 3 extend back to within a slight distance of the heel end of the jacket, and the heel form 4 is omitted. I may also employ a slipper having a hinged heel portion, as shown in Figure 5, and in this case, a heel form 4^a 15 is employed, and has a hinge connection on one side with the rearmost rib on the pad. As shown the hinges are in the form of short links 3^a, which enter holes in the said rib and heel form, and a piece of fabric is secured in the heel form, as shown. By this arrangement the slipper can be used with the heel end either open or closed, and the heel form can be held in closed position by 20 one foot while the other foot is being washed. The sole portion of the jacket is provided with a plurality of holes 11, and by pressing forcibly upon the said sole portions, the arched portions of the ribs are flattened, and with each flattening action of 25 the ribs, water is forced through the holes in the sole portion and against the foot, thus assisting the foot washing process.

In practical use, the slipper is secured in 30 the tub in the manner previously described, and the tub is filled to any desired depth with water, and soap or other cleansing agent is applied to the inside surface of the jacket. A foot is then inserted in the slipper by first inserting the heel in the toe end 35 thereof, and sliding the foot down until it is entirely inclosed by the jacket, which will be held in contact with all parts of the foot by the spring pressure of the ribs. The foot is then moved back and forth in the 40 slipper, and at the same time turned from side to side, so that all parts will be subjected to a scouring action and thereby thoroughly cleansed. A single slipper is used in connection with a foot tub, but with a larger 45 tub, two slippers may be used if desired.

The above described device is particularly useful in cases, where, from physical disability or other causes, the foot washing process is attended with great inconvenience.

Having described my invention, what I claim as new and desire to secure by Letters Patent is:

1. A foot washing slipper, comprising a 60 fabric jacket shaped to partially inclose the foot, and a series of spaced resilient ribs which are secured to the jacket and cause it to conform to the contour of the foot.

2. A foot washing slipper, comprising a 65 fabric jacket which is open along the top, a

series of spaced resilient ribs secured about the jacket and shaped to conform to the cross sectional outline of the foot.

3. A foot washing slipper, comprising a fabric jacket which is open along the top, 70 said opening being increased in width at the toe end of the slipper, and a series of spaced resilient ribs removably secured upon said jacket, and which extend under and around the same and terminate near the edges thereof, said ribs being shaped to conform to the cross sectional outline of the foot, and means for attaching the opposite ends of the slipper to an object.

4. A foot washing slipper, comprising a 80 heavy fabric jacket which is open along the top, and provided with a plurality of holes in the bottom portion thereof, and a series of spaced resilient ribs removably secured upon said jacket and which extend under 85 and around the same and terminate near the edges thereof, said ribs being shaped to conform to the cross sectional outline of the foot, the bottom portions of the ribs being arched.

5. The combination with a tub having an inclined end; of a foot washing slipper comprising a fabric jacket and a series of spaced resilient ribs thereon which cause the jacket to conform to the cross sectional outline of 95 the foot, and means for securing the opposite ends of said slipper to the inclined end of the tub.

6. The combination with a tub having an inclined end; of a foot washing slipper comprising a fabric jacket, open along the top, and a series of spaced resilient ribs thereon which are shaped to conform the jacket to the contour of the foot, hooks connected to the ribs at the opposite ends of the slipper, 100 means in the lower portion of the inclined end of the tub for engaging the hook on the heel end of the slipper, and a coil spring, one end of which is connected to the hook at the toe end of the slipper, the other end of said 105 coil spring terminating in a hook which engages the upper edge of said inclined end, said spring being under tension.

7. A foot washing slipper comprising a fabric jacket open along the top and closed at the heel end thereof, a thin metal heel form around the heel end of the jacket, spaced resilient ribs extending under and around the jacket and terminating near the top edges thereof, said ribs being shaped to 110 conform the jacket to the contour of the foot, holes in said ribs, and split pins which extend through said jacket and through the holes in the ribs.

8. A foot washing slipper, according to 115 claim 7, in which the metal heel form is hinged on one side, to the adjacent rib.

In testimony whereof, I affix my signature.

JAMES M. BURNAP.
